UNITED STATES PATENT OFFICE.

WILLIAM RINTOUL AND ERNEST G. BECKETT, OF STEVENSTON, SCOTLAND, ASSIGNEES
TO NOBEL'S EXPLOSIVES COMPANY, LIMITED, OF STEVENSTON, SCOTLAND.

EXPLOSIVE.

1,298,793.

Specification of Letters Patent.

Patented Apr. 1, 1919.

No Drawing.

Application filed January 3, 1919. Serial No. 269,489.

To all whom it may concern:

Be it known that we, WILLIAM RINTOUL, a subject of the King of Great Britain and Ireland, and ERNEST GEORGE BECKETT, a subject of the King of Great Britain and Ireland, both of Ardeer Factory, Stevenston, Ayrshire, Scotland, have invented certain new and useful Improvements in Explosives, of which the following is a specification.

This invention relates to explosives, and is based on our discovery that the compound dicyandiamidin perchlorate is an explosive, and possesses valuable properties that have not hitherto been known.

The invention consists in preparing dicyandiamidin perchlorate, and in employing it as an explosive alone, or as an ingredient in a composite explosive.

The invention also consists in methods of preparing the dicyandiamidin perchlorate.

The dicyandiamidin perchlorate can be readily prepared from other salts of dicyandiamidin, which in turn are prepared from dicyandiamid by known methods.

According to one method of preparation of the perchlorate, the dicyandiamid is converted into dicyandiamidin sulfate, and to the solution of the latter is added a solution 30 of barium, strontium or calcium perchlorate. The insoluble sulfate is filtered off, and the dicyandiamidin perchlorate recovered from the filtrate by evaporation.

We have also found that the perchlorate 35 can be economically prepared by converting the dicyandiamid into dicyandiamidin hydrochlorid by heating the former with hydrochloric acid, and adding to the solution a hot concentrated solution of sodium perchlorate. The dicyandiamidin perchlorate 40 crystallizes out when the solution is cooled. The above reaction also takes place, however, at ordinary temperatures.

The dicyandiamidin perchlorate may be 45 further purified by recrystallizing it from solution in water.

Dicyandiamidin perchlorate, which may also be called guanyl-urea perchlorate, is approximately represented by the formula:

50 $C_2H_6N_4O \cdot HClO_4$.

We have found it to have the following properties:—

When tested in the Trauzl lead block, it shows an explosive power equal to that of trinitrotoluene, and is so insensitive to mechanical shock that a 10 kilo fall-hammer fails to explode it from a height of 2 meters. Notwithstanding its insensitivity to shock, however, it can be detonated by a No. 3 detonator.

When slowly heated, it begins to melt at a temperature of about 200° C., and is completely melted at about 300° C. It explodes at a temperature of 378° C. The salt is soluble in cold water to the extent of about 65 15 per cent., and is less hygroscopic than potassium nitrate. The absolute density of the pure salt is about 1.8. It has no water of crystallization and is obtained and used as a fine crystalline powder.

This compound is well suited for use as a blasting agent, either alone or as an ingredient in composite explosives. It is also suitable for use as an explosive for military and naval purposes, and generally for 75 such purposes as call for the employment of a high explosive.

As an example of the use of dicyandiamidin perchlorate as the main ingredient in a blasting explosive the following composition 80 is suitable:—

Dicyandiamidin perchlorate	69%
Sodium nitrate	29%
Woodmeal	2%

As an example of the use of dicyandiamidin perchlorate in sensitizing more inert materials the following composition is suitable:—

Ammonium nitrate	80%
Trinitrotoluene	10%
Dicyandiamidin perchlorate	10%

As an example of the use of the explosive for military or naval purposes such as the 95 filling of shells or hand grenades, we load it either by itself in the form of a crystalline powder or in admixture with other substances such as ammonium nitrate or trinitrotoluene. We have found that when used 100

alone dicyandiamidin perchlorate gives excellent results in hand grenades.

The sensitized explosive above mentioned, containing ammonium nitrate, trinitrotoluene and dicyandiamidin perchlorate is especially suitable for use as a shell-filling composition.

Having now described our invention, what we claim as new and desire to secure by Letters Patent is:—

1. An explosive comprising dicyandiamidin perchlorate.

2. An explosive comprising dicyandiamidin perchlorate and a nitrate.

3. An explosive comprising dicyandiamidin perchlorate, a nitrate and a nitro-aromatic body.

4. An explosive comprising dicyandiamidin perchlorate, ammonium nitrate and trinitrotoluene.

In testimony whereof we have signed our names to this specification.

WILLIAM RINTOUL.
E. G. BECKETT.
